UNITED STATES PATENT OFFICE.

ROBERT L. POE, OF CHICAGO, ILLINOIS, ASSIGNOR TO THE POE RANGE COMPANY, OF CHICAGO, ILLINOIS, A CORPORATION OF DELAWARE.

RANGE.

1,344,061.

Specification of Letters Patent. Patented June 22, 1920.

Application filed May 19, 1916. Serial No. 98,532.

To all whom it may concern:

Be it known that I, ROBERT L. POE, a citizen of the United States, residing at Chicago, in the county of Cook and State 5 of Illinois, have invented certain new and useful Improvements in Ranges, of which the following is a specification.

This invention relates to improvements in ranges, and has for its object to provide 10 a new and improved form of range. The object of this invention is to provide a new and improved range in which means are provided to enhance the combustion of the fuel and thereby increase the efficiency and 15 economy of operation.

Still another object is to provide an improved top construction for such a range which will permit ready assembly or disassembly and securing of same in place without 20 bolts or other fastening means.

Still another object consists in providing means to preheat the air supplied for combustion and to utilize such air for insulation of the floor from the range.

Still another object consists in providing 25 spaced apart individual ovens, together with means for controlling the flow of heating gases around and between such ovens.

Another object consists in the provision of 30 means to draw off the fumes, smoke, etc., from the region above the stove.

Another object consists in providing automatic safety dampers in the ovens, such 35 dampers being constructed to automatically open upon the ignition of food cooking in the oven or sudden expansion of the air or gas therein, to prevent explosion when the door is opened.

Another object resides in the provision of 40 new and improved door carrying and operating means for the individual ovens.

These and other objects will be more fully 45 set forth in the following specification and shown in the accompanying drawings, in which;

Figure 1 is a perspective of the range embodying my inventions, portions thereof being broken away for clearance;

Fig. 2 is a vertical longitudinal section 50 through my improved range;

Fig. 3 is a transverse vertical section through the same, a portion of the outlet flue being broken away for clearance;

Fig. 4 is a front elevation of my automatic safety damper; 55

Fig. 5 is a perspective of the same;

Fig. 6 is a horizontal section along the line 6—6 of Fig. 2;

Fig. 7 is a detail plan view of a portion of the grates; 60

Fig. 8 is a detail vertical section of a portion of the air intake and gas circulating space;

Fig. 9 is a similar sectional detail of the end lining construction; 65

Fig. 10 is an end elevation of one of the grate bars;

Fig. 11 is a vertical cross section along the line 11—11 of Fig. 7;

Fig. 12 is a longitudinal section of one of 70 the top plates;

Fig. 13 is a transverse vertical section of the same;

Fig. 14 is a perspective of one of the doors; 75

Fig. 15 is an end elevation of my improved range, portions thereof being broken away for clearance, the front portion being shown in section along the line 15^b—15^b of Fig. 2, and the back portion being shown 80 in section along the line 15^a—15^a of Fig. 2; and

Fig. 16 is a horizontal section along the line 16—16 of Fig. 15.

Like numerals refer to like elements 85 throughout the drawings. 20 indicates individual ovens having the shelves 20^a, for example, and spaced apart from each other and from the ends of the range proper to form circulation spaces 21. At one end of 90

the range is located a fire-box 22 located above the ash chamber 23 and separated therefrom by means of the grate bars 24, which are provided with spaced apart elliptical collars 24^a which terminate in inter-

meshing cogs 24^b. The minor axes of these collars are so related to the major axes that half rotation of the grate bars will permit the passage therethrough of ash or clinkers, and any of the latter which may 100 become caught between the grate bars will be crushed and dropped through upon full rotation of the same, and at the same time the body of the fire will not be allowed to drop into the ash box 23. At the sides of 105

the fire box 22 are provided partition walls.

22^a, 22^b, respectively, the former being located adjacent but spaced from the side wall 20^b of the end oven 20. For insulating said oven from too great heat an additional thickness of metal, or the like, 22^c, is located thereagainst, as clearly shown in Fig. 2, for example. At its upper portion the fire box 22 is provided with the insulated back wall 22^d, see Fig. 6 for example, and in this back wall is provided a damper 25 leading into the main chimney or flue 26. This damper 25 is operable by the shaft 25^a and rod 25^b leading to the front portion of the range, at one end thereof, see Fig. 6. From the lower portion of the fire box 22 and extending to adjacent the bottom of the range at the back thereof is the partition wall 27, see Figs. 6 and 16. Partitions 22^a, 22^b and 27 form the circulation spaces *a*, *b* and *c* respectively, about the fire box and ash box, and the partition walls 22^a, 22^b are provided with apertures communicating with such fire box for a purpose to be hereinafter described.

30 indicates generally the range top located above and spaced from the top of the ovens 20, as shown in Figs. 1 and 2. This top is constructed in sections, as clearly shown in Fig. 2, these sections overlapping, as shown at 30^a, and being provided with reinforcing ribs 30^b. At the rear portion of the range, plates comprising the top 30 are provided with the upstanding flanges 30^c, and inwardly thereof the curved lips 30^d. A portion of the top 30 intermediate the lips 30^d and flanges 30^c rests upon the top of the rear wall 29 of the range, the same also constituting the rear wall of the ovens and being formed of two plates having a lining 29^a of asbestos or other heat insulating material therebetween. At the forward portion of the range the top plates 30 are provided with the depressed flattened under portion 30^e resting on the front wall 29^b of the range, the same constituting the front wall of the ovens 20 and being constructed similarly to the rear wall 29, in that it is provided with a sheet of heat insulating material such as asbestos, located between two spaced apart plates. At their sides the top plates 30 are provided with the cut-away portions 30^f and 30^g, respectively, portions 30^f being intended to overlie and match portions 30^g of the adjacent plates, whereby a continuous flush surface is provided for the top of the stove. The outside plates are also provided with down-turned ends 30^h fitting over and resting on the end walls 29^c of the range. This top construction is such that while presenting a flush and level upper surface it is constructed of a number of sections so arranged as to be readily lifted for access to the interior of the range for cleaning, or the like, and at the same time no bolts or similar fasten-

ing means are required. Furthermore, the portions of the top plates resting upon the end and front walls of the range are so arranged as to permit expansion of the plates relative to the walls of the range when heated, thereby eliminating the possibility of buckling or warping. When it is desired to lift the plates they will pivot about a contact of the curved lips 30^d with the rear wall of the range and permit a hinge action without necessitating a fastening. Between each of the ovens 20 is provided a circulation space 20^c, and at the top of the ovens, extending between adjacent edges, are the dampers 50 resting upon angle irons 50^a carried by the adjacent sides of the ovens, see Fig. 2. These dampers are provided with handles 50^b projecting outwardly in front of the range. These handles are constructed and arranged to coact with a notched quadrant 50^c to retain the dampers 50 in open or closed position, or in positions intermediate such limits. When one of the dampers 50 is in closed position it will restrict the flow of gas between the adjacent pair of ovens. It may also be opened to full position, whereby it will cut off flow of gas beyond and will direct the same through the circulation space between the ovens. Likewise, the damper may be placed in position intermediate these limits to partially divert and partially check the flow of gas. In this manner the heating of individual ovens may be readily controlled, as will be obvious. With these dampers in closed position flow of heating gas is from the fire box over the tops of the ovens to the opposite end of the range downwardly to the bottom thereof, and from thence back past the bottoms of the ovens to an outlet port 105 51 and from thence they may flow through an inclined portion 26^a of main flue 26, as clearly shown in Fig. 2, for example. Located beneath the circulation space 21 is the air duct 52 formed by spaced apart walls 110 52^a. This duct permits entrance of air at the left hand end of the range, as viewed in Fig. 2, to the circulation space *b* from whence it will flow in back of the ash and fire boxes to the circulation space *a* through 115 the space *c* and this air will be discharged through the apertures in partition walls 22^a, 22^b across the fire so as to enhance and greatly increase the combustion of the fuel gas prior to its circulation about the ovens. 120

It will be apparent that by locating my inlet air duct as I have shown, the incoming air will be preheated before reaching the fire box and at the same time will serve to insulate the bottom of the range from the floor. When building a fire in my range I eliminate the circulation of the fuel gas by opening damper 25, whereby a greater draft may be obtained and initial combustion readily obtained. A partition 26^b, see Fig. 125

6, extends partially across from the back of the range to the front at the port 51 to insure proper circulation beneath substantially the entire portion of the oven 20 adjacent the fire box.

It happens in some instances that greasy foods being cooked in an oven will generate combustible gas in such quantity that rapid ignition, amounting in effect to an explosion, will take place, resulting sometimes in the blowing of the doors from the hinges and injuring the chefs, or resulting in a flare-out or explosion when the door is opened to inspect the interior of the oven. To eliminate these explosions and blow-outs, I provide the following construction: Outlet ports 20^h are provided in one side of each of the ovens 20, these ports being surrounded by the casings 20ⁱ, from which project, at each end, the lugs 20^j. Dampers or doors 20^k are provided, the same being provided with trunnions 20^l hingedly mounted in the lugs 20^j, the latter being so arranged that the dampers 20^k will lean inwardly when in closed position, as shown in Fig. 5. These dampers are provided on their inner face with ridges or ribs 20^m to increase their weight, and to locate the center of gravity, when in closed position, inside of the trunnions thereof. A fin 20ⁿ is located adjacent one end of the dampers 20^k, and is preferably made integral therewith, such fin being slotted, as indicated by numeral 20°. An operating lever 60 is provided, the same having an offset portion 60^a engaging the slot 20°, and a handle portion 60^b projecting beyond the front of the range, as shown in Fig. 1. This handle portion 60^b is angularly disposed and will serve to indicate the position of the damper 20^k, as will be obvious. These dampers are so constructed and arranged that when in the position shown in Fig. 2, for example, they will close the ports 20^h, their center of gravity, as explained, being so located with respect to the trunnion mounting as to normally retain them in closed position. Upon sudden ignition, or expansion of gas in the ovens, especially when combustion thereof takes place, the pressure is rapidly increased and immediately opens the dampers 20^k, and before such gas can become sufficiently compressed to blow open the main doors, it will be allowed to flow out from the ovens into the circulation spaces and will be carried by the main flue with the combustion gases. It will thus be seen that these safety dampers operate automatically. They may be set by means of the rods 60, after such opening, or, in some instances, may be manually opened, if so desired, from the outside of the range.

Coacting with my improved range and ovens are the doors 70, located at the front

thereof, and provided with trunnions 70^a, see Fig. 1, mounted in suitable bearings 71 attached in front of the range. Casings 72 are attached to the front of the doors 70 and slidably mounted in said casings are 70 bars 73 having the enlarged upper heads 73^a, apertured at 73^b to fit over and engage the hooks 74 carried on the front of the range. Secured adjacent the lower extremities of the bars 73 are rings 73^c extending 75 through suitable slots 72^a in the casing 72 and attached to the bars 73. An operating rod 75 extends through these rings and may be lifted to move the heads 73^a out of locking engagement with said hooks 74. To 80 counter-balance the door, I provide the counter-balance 76 mounted inside of the front wall of the range and beneath the bottom thereof, as shown in Fig. 3, for example. These counter-balances 76 are provided with the upwardly extending arms 76^a, the same being angularly constructed and extending through suitable slots in the front plate of the range. Apertures 76^b are provided in such arms adjacent their junction with the counter-balances 76, and through these apertures 76^b are inserted suitable pins 77 carried by the bottom of the range, see Fig. 3. At their upper extremities these arms 76^a are provided with pins 90 76^c extending into suitable slots 72^b in the casing 72 and operating to engage such casings, see Fig. 14. It will be apparent that the weight or counter-balance 76 being of proper size and weight the door will be 100 counter-balanced so as to permit its ready movement to open or closed position, while permitting its maintenance in either of such positions. At the same time the counter-balance is removed from sight or possible 105 interference with the user of the range. Clean-out doors 77 are provided in the front wall of the range.

Located above the top of the range proper are the heating shelves 80 extending between and secured to the side plates 81, and similarly attached to the back plate 82. Located adjacent the central portion of this back plate 82 is the flaring or tapered duct member 83 terminating in an outlet flue 84, 110 the upper heating shelves 80 being suitably apertured or recessed to permit location of the outlet duct 83, which terminates above the surface of the range and serves to draw off and exhaust fumes, smoke, or the like, 115 arising from the top of the range and thereby preventing their dissemination. Suitable supporting legs or standards 90 are provided for the range, as shown in Figs. 1 and 2, for example.

It will be apparent from the above description, and the showing of the drawings, that I can admit preheated air to the upper portion of the fire box at which place it will be mingled with the products of combustion 130

of the fuel so as to greatly enhance such combustion. This results in a considerable saving of fuel and increased efficiency of heating. Furthermore, I may control the circulation of the heating gases past, and around the ovens, as desired, to maintain different relative heating effects in such ovens.

It is believed that the operation and construction of my improved range will be so clear from the above description as not to require further explanation herein.

It will also be obvious that my invention is susceptible of modification and improvements, and I do not wish to be restricted to the form shown and described except as defined in the appended claims.

What I claim is:

1. In combination, a range comprising an oven, a fire box, the side walls of said fire box being hollow and provided with means for directing air into said fire box between the surface of the fuel therein and the top of said box, and an air heating supply duct adjacent the range bottom and below said oven and leading to said fire box wall, whereby air drawn through said duct will be heated prior to its introduction into said fire box.

2. A range comprising an outer casing, a fire box and an ash pit positioned therein and spaced from one end thereof to provide an air chamber adjacent one side of said box and pit, an oven mounted in said casing and spaced therefrom and from said fire box and ash pit to provide an air chamber adjacent the other side of said box and pit, a partition wall covering one end of said pit and extending partly into said fire box to provide a communicating passage between said chambers, and a duct opening into one of said chambers at one end and exteriorly of said casing at the other end.

3. A range comprising an outer casing, a fire box and ash pit therein, an oven adjacent said box and pit and spaced therefrom to provide an air chamber therebetween, said air chamber extending from the bottom of said pit to the top of said box, an air duct leading from the exterior of said casing and passing beneath said pit, and a passage adjacent one end of said pit and extending part way into said fire box for connecting said duct with said chamber.

4. A range comprising an outer casing, an oven, an ash pit, a fire box mounted above said pit, the side walls of said box and pit being common, an air chamber adjacent each of said common walls and coextensive therewith, a substantially broad flat passage connecting said chambers, the lower portion of said passage lying adjacent one end of said pit and the upper portion thereof lying within said fire box, the walls of said chamber being apertured for admitting air into said fire box, and ducts for carrying off said air after admission into said box, said ducts extending around said oven to thereby heat the same.

5. A range comprising an outer casing, an oven mounted therein and spaced from one wall thereof, a fire box and ash pit interposed between said oven and wall and spaced from each to provide an air chamber adjacent each side of said box and pit, said chambers extending from the bottom of said pit to the top of said box, a passage connecting said chambers, the lower side of said passage lying below the bottom of said box and the upper side thereof lying above the bottom of said box and in close proximity thereto, an air duct leading to one of said chambers, and means for directing the air after it has passed through said chambers over and around said oven.

6. In combination, a range, a back plate extending upwardly from the top thereof, shelves carried by said back plate, and a fume conveying duct extending through said shelves.

7. In a stove, a casing, a trough-like chamber provided in said casing near one end thereof and spaced from said end and from the bottom of said casing, a grate in said chamber dividing the same into a fire box and an ash pit, a partition plate spaced above said bottom and extending from said ash pit to the other end of said casing, the space intervening between said plate and said bottom together with the space between said chamber and said bottom providing a continuous passage from end to end of said casing, an oven mounted in said casing adjacent said chamber and spaced therefrom, said continuous passage communicating with the spaces on each side of said chamber, an inlet at the far end of said passage, and a series of outlets in the walls of said fire box above the normal level of the fuel therein.

8. In a stove, a casing, an oven mounted therein, a fire box, an ash pit, the side walls of said box and pit being in substantial alinement and spaced from the end wall of said casing and the side of said oven respectively to provide thin flat air circulation passages, said passages extending from the bottom of said pit to the top of said box, and an air heating passage extending along the bottom of said stove and provided with an inlet at one end and communicating with said first named passages at its other end, said first named passages opening into said fire box through a series of outlets provided in the side walls thereof above the normal level of the fuel therein.

9. In a range, the combination with an oven mounted therein and spaced from the

walls thereof, to provide a flue passage therearound for the products of combustion, a door for said oven providing access thereto from the exterior of said range, of an outlet port provided in one wall of said oven and opening into said flue passage, and means to normally close said port, said means being

automatically operable upon a sudden increase in pressure of the gases within said oven to open said port and permit said gases **10** to escape into said flue passage.

In testimony whereof, I have subscribed my name.

ROBERT L. POE.
